CLAIM

The ornamental design for a stethoscope tag with pulse timer, as shown and described.

DESCRIPTION

FIG. 1 is a front perspective view of a stethoscope tag with pulse timer, in accordance with the present invention;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view.
